FEELER-MOTION FOR LOOMS.

1,149,168.

Specification of Letters Patent. Patented Aug. 3, 1915.

Application filed February 5, 1914. Serial No. 816,837.

To all whom it may concern:

Be it known that I, MELVIN L. STONE, a citizen of the United States, and resident of Hopedale, county of Worcester, and State 5 of Massachusetts, have invented an Improvement in Feeler-Motions for Looms, of which the following description, in connection with the accompanying drawings, is a specification, like letters on the drawings representing 10 like parts.

The invention to be hereinafter described relates to filling replenishing looms, wherein a fresh supply of filling is furnished when that in the running shuttle fails or approaches complete exhaustion; and more 15 particularly the present invention has reference to the feeler motions of such looms.

As well understood by those skilled in the art, feeler motion devices intermittently feel 20 for the filling in the running shuttle, and when the filling has become exhausted or exhausted to a predetermined extent, such devices cause or permit the operation of the filling replenishing mechanism at the proper 25 time to automatically furnish the loom with a fresh supply of filling.

Various forms of feeler motions or filling 30 exhaustion indicating mechanisms have been devised, some of which have been employed in connection with certain initial windings at a particular part of the bobbin or carrier, others of which have depended for their 35 operation upon contact with a particular part of the bobbin itself, as it becomes exposed. In all such cases, however, it is necessary that the bobbin or carrier in the shuttle should occupy a predetermined position in the shuttle box, otherwise the feeler motion devices will fail to act upon the particular 40 part of the filling or bobbin intended, in which case improper indication and consequent action or inaction of the filling replenishing mechanism will result. This defective condition will arise, for instance, when 45 the shuttle rebounds in its box, or fails to reach its proper position therein.

The aims and purposes of the present invention are to provide a feeler motion for looms, wherein the parts are so constructed 50 and related that a more perfect detection of filling exhaustion may be had and the proper detecting function be discharged even though the shuttle may rebound in its box or for any other reason fail to be properly po-

sitioned therein, all of which will best be 55 made clear from the following description and accompanying drawing of one form of means for carrying the invention into practical effect, it being understood that details may be varied within the true scope of the 60 invention as defined by the claims.

In the drawings:—Figure 1 is a plan view of a filling feeler mechanism embodying the present invention, showing also part of a shuttle and filling carrier therein, portions of 65 the shuttle box being omitted for clearness of illustration; Fig. 2 is a section on line 2—2, Fig. 1; Fig. 3 is an enlarged diagrammatic view showing parts of the feeler motion devices acting upon a filling carrier which has 70 become practically exhausted of filling and has rebounded in the shuttle box; Fig. 4 is a section on the line 4—4, Fig. 3, showing more particularly the relative position of the 75 detectors; and Fig. 5 is a sectional view of a bobbin of slightly modified form.

In the following exploitation of the invention the replenishment of filling is to be effected by ejecting the practically exhausted filling carrier or bobbin in the shuttle and 80 introducing a carrier or bobbin having a fresh supply of filling; but so far as the essentials of the present invention are concerned, such replenishment may be otherwise effected, as by changing shuttles. 85

As shown by the drawings, the shuttle 1 is or may be of any usual character adapted for use in a filling replenishing loom and is preferably provided with holding jaws 2 to engage the head 3 of the removable filling 90 carrier or bobbin 4. The front wall of the shuttle 1 is preferably so formed that the feeler motion devices may come into co-acting relation with the filling carrier or bobbin and its load as the lay moves to front 95 position, and in the present form of the invention the wall of the shuttle is provided with an opening 5 of suitable size and character, through which the feeler motion devices, to be described, may enter, in usual manner. Similarly the front wall of the shuttle box (not shown) may be provided with a passage-way or opening with which the opening or slot 5 in the shuttle may register when the shuttle is boxed at the 105 feeler side of the loom. In these respects the shuttle may be as usual, except that the opening 5 therethrough may be longer to en-

able the feeler motion devices to enter and perform their function even though the shuttle may not be properly positioned in its box either by reason of rebound or failure 5 to reach its intended position.

Mounted upon suitable means opposite the shuttle box 6 at the feeler side of the loom is a support 7 adapted to sustain the feeler slide 8 in a manner to permit said 10 slide to move longitudinally. As a convenient and good practical construction for such purpose, the support 7 may be formed as a casing chambered at 9 for the passage of the shank 10 of the feeler slide, and to maintain 15 the feeler slide normally projected toward the lay suitable means, such as a spring 11, may be interposed between a shoulder 12 on the shank and the opposite end wall of the chamber 9, the construction being such that 20 the spring normally holds the feeler slide projected toward the lay but permits such slide to yield longitudinally upon the application of force, as will presently appear. The casing 7 may be held in place conveniently 25 by appropriate means, such as screws 13, Fig. 1.

Extending at one side of the support or casing 7 is a guideway for the end portion of a transmitter 14, Figs. 1, 2 and 3, such 30 guideway being preferably formed as a slot 15 in a flange 16 projecting from the support or casing 7. The parts thus far described may be substantially as heretofore and as set forth in the patent to Rainville, 35 No. 1,040,409, of October 8, 1912, or they may be changed to suit conditions of use. Herein it will be understood that the actuation of the transmitter 14 by the feeler mechanism to be described, is designed to 40 cause or permit filling replenishment, but as such replenishing mechanism and the association therewith of a transmitter are well understood by those skilled in the art, the details thereof are not illustrated herein.

As hereinbefore noted, one of the purposes 45 of the present invention is to secure proper action of the feeler motion devices, and perforce of the replenishing or other mechanisms under their control, even though the 50 shuttle or filling carrier therein should not be properly positioned in the shuttle box. As one means to this end the filling carrier or bobbin 4 is provided with certain preliminary or initial windings of filling sufficient 55 to permit one, two, or more picks of the shuttle even after the working load of filling has become practically exhausted, and the feeler motion devices are so contrived, that when the working load of filling has 60 reached a point where replenishment is desirable, they will act in conjunction with said preliminary or initial windings to cause or permit filling replenishment even though the shuttle or filling carrier may not be properly 65 positioned in the shuttle box, a condi-

tion that may happen when the shuttle rebounds or does not reach the limit of its intended movement.

In the form of the invention illustrated, the preliminary or initial windings upon the filling carrier or bobbin are preferably placed at a recessed portion of said carrier or bobbin. As illustrated in Fig. 3, for instance, the filling carrier or bobbin 4 may be provided with a ferrule 17 having a recessed portion at 18 upon which the preliminary or initial windings 19 may be placed. This ferrule 17 may be spun or otherwise secured to the filling carrier or bobbin. While the filling carrier with the ferrule 17 is a good practical form of carrier, the invention, it is to be understood, is not restricted thereto, because the bobbin or filling carrier may be made as indicated in Fig. 3, wherein it is substantially of the general form of that shown in Fig. 3, with the ferrule 17 omitted, and in which case the recess for the initial or preliminary windings is formed at 18' directly upon the body of the bobbin or carrier 4'. The preliminary windings, as indicated in Fig. 3, are of course exaggerated somewhat, in order to make clear the characteristics and operation of the invention.

The feeler slide 8 is extended toward the rear of the loom or toward the shuttle box, and has a feeler head 20 which extends in a longitudinal direction of the filling carrier to an extent greater than the preliminary or initial windings 19 with which the filling carrier or the bobbin is supplied. In the present form of the invention the feeler head 20 is of slightly greater width than the recessed portion 18 of the ferrule 17, or the recessed portion 18' of the bobbin or carrier.

Projecting upward from the feeler slide 8 are the lugs 21 carrying the pivotal support or rod 22 for a series of levers 23. These levers 23 may, for identification, be 110 known as detectors, because as will presently appear, they detect the substantial exhaustion of the filling from the carrier or bobbin and by such detection cause or permit replenishment of the filling.

As heretofore noted, there are a series of these detectors 23, preferably three, as indicated in Figs. 1 and 3, and they are substantially alike. Each is provided with a detector head 24 which, as the detectors 23 120 move about their pivotal support 22, rise and fall in grooves or openings in the feeler head 20, substantially as indicated in Figs. 2 and 3.

The end portions 25 of the detector heads 125 24 normally extend slightly beyond the edge of the feeler head, as indicated in Fig. 3. The detectors 23 are so balanced upon their pivotal support 22 that the longer arms thereof which carry the shouldered portions 130

26, are normally depressed, so that should the feeler slide 8 be moved toward the front of the loom and the detectors be not turned upon their pivotal support, the shouldered portions 26 of the detectors would meet the transmitter 14 as they moved to the right, Figs. 2 and 4, and cause the said transmitter to be moved in its guide 15 to thereby initiate or permit filling replenishment as hereinbefore pointed out.

It may be advisable to provide means for limiting the rising and falling movements of the shouldered portions of the detectors and to this end suitable stops 27 and 28 may be provided, the former being preferably of the usual knife blade character, while the latter may comprise a plate or arm 28 projecting over the shouldered portions of the detectors.

From the construction described, it will be apparent that when the carrier or bobbin 14 is supplied with a working quantity of filling, as indicated in Fig. 1, on the forward movement of the lay the ends 25 of the detectors will be first met by the filling, thereby turning the detectors about their pivotal support 22 so that as the feeler slide 8 moves toward the front of the loom, or to the right, in Figs. 1 and 2, the shouldered portions 26 of detectors will not engage the transmitter. If, however, the filling has become practically exhausted, and the shuttle has been properly boxed directly in front of the feeler and detector heads, the feeler head 20 will engage the shouldered portions of the filling carrier or bobbin at each end of the recess 18 therein, but as the initial windings 19 are not of sufficient diameter to contact with and find the detectors 23, they will remain depressed, with the result that as the feeler slide moves toward the front of the loom the shouldered portions 26 of the detectors will engage and move the transmitter 14, thereby initiating or permitting filling replenishment.

Should the filling have become practically exhausted and the shuttle be not properly positioned in the box, as for instance, should the shuttle rebound or fail to reach its proper location in the box, the recessed portion 18 of the carrier or bobbin will be located more or less to one side or the other of the feeler device. In this event one or the other side of the feeler head will engage the bobbin or carrier beyond the initial windings; and if the displacement of the shuttle be considerable, one or more of the detector heads may likewise engage the bobbin or carrier beyond the initial windings, with the result that those detectors the heads of which are thus engaged by the bobbin or carrier will be tilted on their pivotal supports, while that one of the detectors the head of which does not engage the bobbin or carrier but is positioned opposite the initial

windings, will not be tilted, so that as the feeler slide 8 moves toward the front of the loom, the detector which has not been tilted will have its shouldered portion 26 engage the transmitter 14 and initiate or permit filling replenishment, as hereinbefore indicated.

In Fig. 3, the parts are shown in the relation they will assume if, for instance, the shuttle had entered its box and rebounded. In this event the lower portion 20 of the feeler head, as well as the lower detector head 25, Fig. 3, will engage the bobbin or carrier, and the detector whose head has thus engaged the bobbin or carrier will be tilted on its support into inoperative position; while the other two detectors, the heads of which are opposite the initial windings 19, will not be tilted, with the result that as the feeler slide 8 moves toward the front of the loom under the advancing movement of the filling carrier or bobbin with which the lower portion of the head 20 is engaged, the two detectors, the heads of which are opposite the initial windings will have their shouldered portions 26 engage with the transmitter 14 and cause or permit filling replenishment.

The same characteristic operation will take place should the shuttle not reach the limit of its intended movement in the box, as will readily be understood; and by providing a plurality of detectors intermediate the two end portions 20 of the feeler head, the intended operation of the feeler motion devices will be carried into effect, notwithstanding considerable misplacement of the shuttle in its box.

While the invention has been described as embodied in certain preferred details of mechanical devices, it is to be understood that it is not necessarily limited thereto, but that such devices may be varied in character and relation within the true scope of the invention, as pointed out by the claims.

What is claimed is:—

1. A feeler motion for looms, comprising in combination, a shuttle, a carrier therein having a recessed portion on which initial windings are laid, a feeler having a head and a plurality of independent detectors for entering the shuttle to detect the substantial exhaustion of the filling therein, said feeler head being of greater extent longitudinally of the shuttle than the recessed portion of the carrier therein to bridge said windings and to contact with the carrier at one side of said windings when the filling has become practically exhausted and the shuttle is not properly boxed.

2. A feeler motion for filling replenishing looms, comprising a feeler having a slotted head and a plurality of detectors movable transversely of the head in the slots thereof, a shuttle containing a carrier having a re-

4
 cessed portion over which initial windings are laid, said head and plurality of detectors adapted to enter the shuttle to detect substantial exhaustion of the filling therein and 5 being longitudinally of greater extent than the initial windings on the carrier therein to bridge said windings when the shuttle is properly boxed and to engage the carrier at one end of said windings when the shuttle 10 is improperly boxed and the filling has become practically exhausted.

3. A feeler motion for looms, comprising a feeler having a head portion of greater longitudinal extent than and adapted to 15 bridge a longitudinal recess in a filling carrier or bobbin when the shuttle is in proper position, and a plurality of detectors having detector portions between the sides of the feeler head, one at least, of which acts individually and independently of the others and in conjunction with the feeler to indicate substantial exhaustion of filling when the shuttle is not in its proper position.

4. A feeler motion for looms, comprising 25 a feeler slide having a feeler head and a plurality of detectors mounted side by side on said head between the side portions thereof, in combination with a shuttle containing a carrier having a depressed datum surface 30 provided with initial windings, the side portions of the feeler head being separated longitudinally of the shuttle to a greater extent than the longitudinal limits of the initial windings on the carrier therein to 35 bridge said windings when the shuttle is properly boxed and to engage the carrier at one side of said windings when the shuttle is improperly boxed and the filling has become substantially exhausted.

40 5. In a feeler motion for looms, the com-

bination of a shuttle, a filling carrier having a recessed datum surface portion for containing initial windings of filling, a feeler having a head of an extent longitudinally of the shuttle greater than said datum 45 surface, a plurality of detectors pivotally mounted on said head and having end portions projecting beyond the head, said head being adapted to enter the shuttle and bridge the datum surface when the shuttle 50 is properly boxed and said head and one or more of said detectors contacting with the carrier beyond the datum surface when the shuttle is improperly boxed.

6. A feeler motion comprising a feeler head provided with a plurality of slots between the side portions thereof, a plurality of detectors pivotally connected to said head and having end portions movable transversely of said slots to detect the substantial 60 exhaustion of the filling in the shuttle.

7. In a loom, the combination of a shuttle, a filling carrier having a recessed portion to contain initial or preliminary windings of filling, a feeler having a feeler head and 65 a plurality of independently movable detectors having detector portions disposed opposite said recessed portion when the shuttle is properly positioned in its box and having at least one of said detector portions opposite 70 said recessed portion of the carrier when the shuttle is improperly positioned in its box.

In testimony whereof, I have signed my name to this specification, in the presence of 75 two subscribing witnesses.

MELVIN L. STONE.
